UNITED STATES PATENT OFFICE

GEORGE ELLISON AND JAMES ANDERSON, OF BIRMINGHAM, ENGLAND

ALTERNATING-ELECTRIC-CURRENT INTERRUPTER

Application filed February 25, 1930, Serial No. 431,294, and in Great Britain March 4, 1929.

This invention has for its object to provide improved means for interrupting alternating electric currents.

The invention comprises the combination 5 of a plurality of coaxial contact pieces which are arranged in series and are contained in compartments separated by insulating dia- phragms, and means for producing a radial magnetic field in association with the contact 10 pieces.

The accompanying drawing illustrates dia- grammatically one mode of carrying the invention into effect.

Referring to the diagram, we employ a plu- 15 rality of movable annular contact pieces *a* which are arranged coaxially. Preferably each contact piece consists of a ring of copper which is electro-plated with a coating of zinc or cadmium.

20 A convenient number of these contact pieces is employed and each is carried by a disc or diaphragm *b* of flexible insulating ma- terial. The contact pieces are contained within an annular iron container *c* which 25 forms one pole of an electromagnet excited by a winding *d* in series with the contact pieces, the other pole being formed by a central bar *e*, the arrangement giving a radial magnetic field across the space between the parts *c*, *e*. The diaphragms *b* are attached 30 at their inner and outer peripheries to the parts *c*, *e* in any convenient manner, and they form a plurality of chambers each containing the adjacent parts of a pair of contact pieces. Preferably each diaphragm is 35 perforated by oppositely arranged holes *f*, and the container *c* is also perforated as shown at *g*. The whole may be immersed in oil. The contact piece *h* at one end of the series

40 is fixed, and the one *i* at the other end is carried on a movable member *j* which can be actuated in any convenient manner. Also the contact pieces *h*, *i* are connected to the circuit to be controlled by any appropriate means. The circuit is closed when by means 45 of the member *j* all the contact pieces are pressed together. On withdrawing the member *j*, the contacts are separated, either by gravity, or the elasticity of the dia- phragms, or under the action of springs, or

50 by any other suitable means, and, under the influence of the radial magnetic field, each of the arcs set up between the contact pieces is caused to move in a circular path between the faces of the contact pieces, and is thereby rapidly extinguished. The amount of separation allowed between each pair of contacts need not be large, from three to eight thou- sandths of an inch being usually sufficient. The number of movable contact pieces pro- 60 vided depends upon the voltage of the system to be controlled, an allowance of about four hundred volts per contact being usually satisfactory.

The invention is especially adapted for the 65 switches used for controlling large amounts of electrical energy, but it may be applied to any system in which it is necessary to avoid excessive arcing.

It will be understood that the invention is 70 not limited to the example above described, and the constructional details may be varied as required.

Having thus described our invention what 75 we claim as new and desire to secure by Letters Patent is:—

1. In alternating electric current inter- rupters, the combination of a plurality of coaxial contact pieces arranged in series, an outer container, diaphragms of insulating 80 material arranged across the interior of the container and forming compartments each of which encloses a pair of contact pieces, (a contact piece being secured to each side of each diaphragm and interconnected), and means for producing a radial magnetic field in association with the contact pieces, sub- stantially as described.

2. In alternating electric current inter- rupters, the combination of an outer iron 90 container, a central axial iron core, dia- phragms of insulating material arranged parallel with each other and dividing the space between the core and container into a number of separate compartments, a pair of 95 coaxial annular contact pieces secured in electrical connection with each other to the opposite sides of each diaphragm, the whole of the contact rings forming a group of contacts in series with each other, a fixed contact

situated within the container, at one end of the said group of contacts, a movable contact situated at the other end of the group whereby all the contact rings can be pressed into contact with each other, and a magnetic winding on the core substantially as described.

In testimony whereof we have signed our names to this specification.

10   **GEORGE ELLISON.**
                         JAMES ANDERSON.
